SOUND VOLUME REGULATOR

Joseph Béthenod, Paris, France, assignor to Compagnie Générale de Télégraphie Sans Fil, Paris, France, a corporation of France

Application April 9, 1931, Serial No. 528,779
In France April 12, 1930

3 Claims. (Cl. 179—100.4)

The present invention relates to improvements in apparatus for regulating the volume of sound produced in gramophones and similar apparatus employing electric amplifiers (generally thermionic valve apparatus). The invention provides a regulation under much more satisfactory conditions than those obtaining with hitherto known methods and will be readily understood with reference to the accompanying diagram 10 which illustrates an installation arranged according to this invention.

Referring to the diagram, a gramophone "pick-up" 1 of the well-known electromagnetic type is arranged to deliver current to a group 15 of inductance windings 2, coupled in series with one another. In order to regulate the volume of sound emitted by a loudspeaker connected to the "pick-up" through the medium of an electronic amplifier, a commutator 3 is provided, the 20 contacts of which are electrically connected to the bobbins 2 as indicated.

The variable potential which may thus be delivered to the leads 4, 5, bears a constant relationship to the electromotive force induced in 25 the "pick-up" whatever may be the selected position of the movable rider of the commutator 3, provided that the time constant of each of the bobbins 2, that is, the relation of the inductance thereof to the ohmic resistance is of relatively 30 the same value as that of the winding of the "pick-up" itself, which it is always possible to ensure. If, for example, the potential thus obtained is applied to the grid circuit of a three electrode valve 6 which is arranged to supply 35 the amplifier feeding the loudspeaker; a perfect solution of the problem of the control of the volume of the sound is thus obtained in a very simple manner, since it is sufficient to actuate 40 the handle of the rider of the commutator 3 to produce an effect comparable to that which would be obtained theoretically if it were possible to modify directly at will the electromotive force produced in the "pick-up" without altering 45 the constants of the various circuits involved. Naturally, the number and the constitution of the windings 2 are arbitrary according to circumstances; on the other hand, it is possible in constructing the windings 2, to depart intentionally 50 from the time constant of the "pick-up" itself with a view to the production of certain desired results in the sound produced by the loudspeaker.

What is claimed is:

1. Means adapted to regulate the volume of sound produced by a phonographic apparatus provided with an electrical pick-up, comprising the combination of a plurality of separate and distinct self-inductive coils which individually have a time constant substantially equal to that of the pick-up and which coils as a group are connected in series in the output circuit of the pick-up, means for applying at least a portion of the total self-inductance of all of said coils by applying the entire self-inductance of at least one of said coils to the input circuit of a thermionic tube amplifier including a switch member in said input circuit and individual leads connected to said coils with each of which leads said switch member may be brought into contact, at will, and means provided by said amplifier for indicating the volume of sound. 5
2. Means adapted to regulate the volume of sound produced by a phonographic apparatus provided with an electrical pick-up, comprising the combination of a plurality of separate, distinct, resistive and self-inductive but non-mutually inductive coils which individually have a time constant substantially equal to that of the pick-up and which coils as a group are connected in series in the output circuit of the pick-up, means for applying at least a portion of the total self-inductance of all of said coils by applying the entire self-inductance of one or more of said coils to the input circuit of a thermionic tube amplifier, and means provided by said amplifier for indicating the volume of sound. 10
3. Means adapted to regulate the volume of sound produced by a phonographic apparatus provided with an electrical pick-up, comprising the combination of a plurality of separate, distinct, resistive and self-inductive but non-mutually inductive coils which individually have a time constant substantially equal to that of the pick-up and which coils as a group are connected in series in the output circuit of the pick-up, means for applying at least a portion of the total self-inductance of all of said coils by applying the entire self-inductance of one or more of said coils to the input circuit of a thermionic tube amplifier including a switch member in said input circuit and individual leads connected to said coils with each of which leads said switch member may be brought into contact, at will, and means provided by said amplifier for indicating the volume of sound. 15
4. Means adapted to regulate the volume of sound produced by a phonographic apparatus provided with an electrical pick-up, comprising the combination of a plurality of separate, distinct, resistive and self-inductive but non-mutually inductive coils which individually have a time constant substantially equal to that of the pick-up and which coils as a group are connected in series in the output circuit of the pick-up, means for applying at least a portion of the total self-inductance of all of said coils by applying the entire self-inductance of one or more of said coils to the input circuit of a thermionic tube amplifier including a switch member in said input circuit and individual leads connected to said coils with each of which leads said switch member may be brought into contact, at will, and means provided by said amplifier for indicating the volume of sound. 20
5. Means adapted to regulate the volume of sound produced by a phonographic apparatus provided with an electrical pick-up, comprising the combination of a plurality of separate, distinct, resistive and self-inductive but non-mutually inductive coils which individually have a time constant substantially equal to that of the pick-up and which coils as a group are connected in series in the output circuit of the pick-up, means for applying at least a portion of the total self-inductance of all of said coils by applying the entire self-inductance of one or more of said coils to the input circuit of a thermionic tube amplifier, and means provided by said amplifier for indicating the volume of sound. 25
6. Means adapted to regulate the volume of sound produced by a phonographic apparatus provided with an electrical pick-up, comprising the combination of a plurality of separate, distinct, resistive and self-inductive but non-mutually inductive coils which individually have a time constant substantially equal to that of the pick-up and which coils as a group are connected in series in the output circuit of the pick-up, means for applying at least a portion of the total self-inductance of all of said coils by applying the entire self-inductance of one or more of said coils to the input circuit of a thermionic tube amplifier including a switch member in said input circuit and individual leads connected to said coils with each of which leads said switch member may be brought into contact, at will, and means provided by said amplifier for indicating the volume of sound. 30
7. Means adapted to regulate the volume of sound produced by a phonographic apparatus provided with an electrical pick-up, comprising the combination of a plurality of separate, distinct, resistive and self-inductive but non-mutually inductive coils which individually have a time constant substantially equal to that of the pick-up and which coils as a group are connected in series in the output circuit of the pick-up, means for applying at least a portion of the total self-inductance of all of said coils by applying the entire self-inductance of one or more of said coils to the input circuit of a thermionic tube amplifier including a switch member in said input circuit and individual leads connected to said coils with each of which leads said switch member may be brought into contact, at will, and means provided by said amplifier for indicating the volume of sound. 35
8. Means adapted to regulate the volume of sound produced by a phonographic apparatus provided with an electrical pick-up, comprising the combination of a plurality of separate, distinct, resistive and self-inductive but non-mutually inductive coils which individually have a time constant substantially equal to that of the pick-up and which coils as a group are connected in series in the output circuit of the pick-up, means for applying at least a portion of the total self-inductance of all of said coils by applying the entire self-inductance of one or more of said coils to the input circuit of a thermionic tube amplifier including a switch member in said input circuit and individual leads connected to said coils with each of which leads said switch member may be brought into contact, at will, and means provided by said amplifier for indicating the volume of sound. 40
9. Means adapted to regulate the volume of sound produced by a phonographic apparatus provided with an electrical pick-up, comprising the combination of a plurality of separate, distinct, resistive and self-inductive but non-mutually inductive coils which individually have a time constant substantially equal to that of the pick-up and which coils as a group are connected in series in the output circuit of the pick-up, means for applying at least a portion of the total self-inductance of all of said coils by applying the entire self-inductance of one or more of said coils to the input circuit of a thermionic tube amplifier including a switch member in said input circuit and individual leads connected to said coils with each of which leads said switch member may be brought into contact, at will, and means provided by said amplifier for indicating the volume of sound. 45
10. Means adapted to regulate the volume of sound produced by a phonographic apparatus provided with an electrical pick-up, comprising the combination of a plurality of separate, distinct, resistive and self-inductive but non-mutually inductive coils which individually have a time constant substantially equal to that of the pick-up and which coils as a group are connected in series in the output circuit of the pick-up, means for applying at least a portion of the total self-inductance of all of said coils by applying the entire self-inductance of one or more of said coils to the input circuit of a thermionic tube amplifier including a switch member in said input circuit and individual leads connected to said coils with each of which leads said switch member may be brought into contact, at will, and means provided by said amplifier for indicating the volume of sound. 50
